PRODUCTION OF UNSATURATED CARBONYLIC COMPOUNDS

Robert M. Cole, Oakland, Clarence L. Dunn, Berkeley, and Gino J. Pierotti, Albany, Calif., assignors to Shell Development Company, San Francisco, Calif., a corporation of Delaware

Application July 31, 1950, Serial No. 176,854

7 Claims. (Cl. 260—604)

1

This invention relates to the production of alpha,beta-unsaturated carbonylic compounds by the oxidation of hydrocarbons having at least three carbon atoms to the molecule. The invention relates more particularly to the production of alpha-methylene aldehydes and ketones by the oxidation of olefins having at least three carbon atoms to the molecule. A particular aspect of the invention relates to the production of alpha-methylene aldehydes having from three to four carbon atoms to the molecule by the oxidation of normally gaseous hydrocarbons comprising the corresponding olefins.

Production of alpha,beta-unsaturated carbonylic compounds on a practical scale generally results in the obtaining of a crude product comprising a desired unsaturated carbonylic compound in admixture with substantial amounts of by-products unavoidably formed during the process. The ability to utilize the unsaturated carbonylic compounds, such as the alpha-methylene aldehydes and/or ketones efficiently in many fields of application is often dependent upon the absence therein of any substantial amount of impurities. The large-scale production of an alpha,beta-unsaturated aldehyde or ketone of relatively high purity is, of necessity, limited to methods enabling the obtaining of a product comprising the unsaturated carbonylic compound in admixture with impurities which are readily separable therefrom by available practical scale separating means. Thus, the production of acrolein from such starting materials, as for example, acetaldehyde and formaldehyde under carefully controlled conditions often enables the attainment of a product comprising the acrolein in admixture with impurities consisting essentially of acetaldehyde, formaldehyde and relatively high-boiling organic materials. All of such impurities are readily separable from the acrolein on a practical scale by methods available heretofore comprising such steps as simple fractionation, water scrubbing, distillation, and the like. Although acrolein of relatively high purity can be obtained by such methods these processes are generally handicapped by unavailability at sufficiently low cost of the starting materials. A particularly valuable source of the unsaturated carbonylic compounds comprises the products obtained by the oxidation of the readily available hydrocarbons. It has been found recently that the readily available hydrocarbons comprising olefins having at least three carbon atoms to the molecule, can be converted efficiently to products consisting predominantly of alpha,beta-unsaturated carbonylic compounds, such as, for example, the alpha,beta-unsaturated aliphatic aldehydes and ketones by catalytic oxidation. Thus,

2

unsaturated carbonylic compounds consisting essentially of acrolein and methacrolein are obtained by the catalytic oxidation of propylene and isobutylene, respectively. The effluence from the hydrocarbon oxidizing zone in such processes, however, is an exceedingly complex mixture and contains the desired unsaturated carbonylic compound in admixture with saturated carbonylic compounds such as saturated aldehydes and ketones inseparable therefrom on a practical scale by the methods applicable to the treatment of less complex mixtures. The production of an alpha,beta-unsaturated aliphatic aldehyde from the corresponding olefin, such as, for example, 5 the production of acrolein from propylene, results in the production of a complex mixture comprising the acrolein in admixture not only with readily separable impurities such as formaldehyde, acetaldehyde, and high-boiling material but 10 also close-boiling carbonylic compounds such as, for example, propionaldehyde and acetone, inseparable therefrom on a practical scale by simple distillation, water scrubbing, or the like. Inability to effect the efficient and yet substantially 15 complete recovery of the unsaturated aldehydes from the hydrocarbon oxidation products containing them has militated against any full realization of the substantial advantages as a source of these highly desirable and valuable compounds. 20 In co-pending applications Serial Nos. 1,314, now U. S. Patent No. 2,514,966, 49,816, now U. S. Patent No. 2,514,967 and 84,074 there have been described and claimed methods for the recovery of alpha,beta-unsaturated aldehydes from the crude alpha,beta-unsaturated aldehydes comprising saturated carbonylic impurities having boiling temperatures approximating those of the alpha,beta-unsaturated aldehydes. These processes, however, generally 25 necessitate the initial separation of a crude alpha,beta-unsaturated aldehyde from the effluence from the hydrocarbon oxidizing zone. The separation of a crude unsaturated aldehyde may be effected by scrubbing the hydrocarbon oxidation products emanating from the hydrocarbon oxidizing zone with water to effect a substantially complete separation of normally gaseous materials, generally including fixed gases and unconverted hydrocarbons, from carbonylic hydrocarbon reaction products. Such separation generally necessitated the use of exceedingly 30 large quantities of water. The passage of such inordinately large amounts of water through such scrubbing zone not only renders difficult the 35 maintenance of relatively constant conditions conducive to the attainment of optimum results, but materially increases initial installation and 40 overall operating costs of the process. In such 45 50 55

method of operation not only all of the inert gas but also substantially all unconverted hydrocarbons are passed overhead from the scrubber. Since operation of the process on a practical scale necessitates the recycling of unconverted hydrocarbons, inordinately large volumes of material must be passed overhead from the scrubber to a suitable recycle recovery system in such processes. Further difficulties inherent in such methods of operation as used heretofore reside in the fact that the maximum permissible pressure within the product scrubber is governed by the pressure at which the hydrocarbon components of the charge thereto begin to condense. The use of water as scrubbing medium generally allows relatively little variation of conditions within the scrubber without incurring either the condensation of excessive amounts of hydrocarbon or the highly undesirable consequence involving the passage of carbonylic constituents overhead.

It is an object of the present invention to provide an improved process enabling the more efficient production of alpha,beta-unsaturated carbonylic compounds by the oxidation of hydrocarbons wherein the above difficulties are obviated to at least a substantial degree.

Another object of the invention is the provision of an improved process enabling the more efficient production of alpha,beta-unsaturated carbonylic compounds by the oxidation of olefinic hydrocarbons wherein difficulties heretofore encountered in the separation of carbonylic compounds from the hydrocarbon oxidation zone effluence are obviated to at least a substantial degree.

A more particular object of the invention is the provision of an improved process enabling the more efficient production of alpha,beta-unsaturated hydrocarbons having from three to four carbon atoms to the molecule by the oxidation of hydrocarbons comprising olefins having from three to four carbon atoms to the molecule.

A still more particular object of the invention is the provision of an improved process enabling the more efficient product of methacrolein by the oxidation of normally gaseous hydrocarbons comprising isobutylene. Other objects and advantages of the invention will become apparent from the following detailed description there.

It has been found, as disclosed and claimed in co-pending application Serial No. 176,853, filed July 31, 1950, of which the present application is a continuation-in-part that substantially improved production of alpha,beta-unsaturated carbonylic compounds, by catalytic oxidation of hydrocarbons comprising olefins, is obtained by introducing at least a part of the olefinic hydrocarbon feed to the process into an absorption zone wherein said feed is brought into direct contact with effluence from the hydrocarbon oxidation zone under conditions effecting the separation of carbonylic components from said reactor effluence with the formation of a fraction in the liquid state comprising said carbonylic compounds and said hydrocarbon feed and a gaseous fraction comprising fixed gases. Carbonylic compounds are recovered from the fraction separated in the liquid state in the absorption zone, and hydrocarbon components remaining after such separation are introduced into the hydrocarbon oxidation zone of the process wherein they are subjected to conditions resulting in the oxidation of hydrocarbons to reaction prod-

ucts comprising alpha,beta-unsaturated carbonylic compounds.

Realization to the full of the advantages inherent in the improved process, however, often are handicapped by the formation in the system of carbonylic by-products which are inseparable from, or can be separated only with great difficulty from, the hydrocarbons to be oxidized by such means as simple distillation, ordinary fractionation, and the like. Contacting the hydrocarbons to be oxidized with oxidation zone effluence prior to their passage into the oxidation zone will often result in an accumulation of such by-product carbonylic impurities in the system rendering difficult the maintenance of optimum operating conditions and the efficient obtaining of maximum yields. It has now been found that these further difficulties are obviated to at least a substantial degree by subjecting simultaneously both the contaminated hydrocarbons to be oxidized and the crude alpha,beta-unsaturated carbonylic product to a common purification step which removes the carbonylic impurity from said contaminated hydrocarbons to be oxidized while simultaneously effecting the purification of the desired alpha,beta-unsaturated carbonylic product. For example, in the production, in accordance with the invention, of an alpha,beta-unsaturated carbonylic compound, such as methacrolein, by the controlled catalytic oxidation of normally gaseous hydrocarbons comprising isobutylene, the normally gaseous hydrocarbons to be oxidized are passed in the liquid state through an absorption zone countercurrent to methacrolein-containing effluence from the hydrocarbon oxidation zone, thereby separating methacrolein-containing carbonylic compounds from the effluence of the hydrocarbon oxidizing zone with the formation of a liquid fraction consisting essentially of hydrocarbons comprising isobutylene and methacrolein-containing carbonylic compounds and a gaseous fraction comprising fixed gases. The liquid fraction formed in the absorption zone is fractionated to separate therefrom a fraction consisting essentially of normally gaseous hydrocarbons comprising isobutylene unavoidably contaminated by the presence therein of carbonylic impurities and a fraction comprising methacrolein-containing carbonylic compounds. The fraction comprising methacrolein-containing carbonylic compounds is subjected to a liquid phase solvent extraction using water as the selective solvent in the presence of said contaminated normally gaseous hydrocarbon fraction comprising isobutylene as a secondary solvent, thereby forming a raffinate phase consisting essentially of methacrolein and isobutylene substantially free of contaminant carbonylic compounds. Isobutylene, substantially free of carbonylic compounds is distilled from the raffinate phase, thereby leaving as residue the desired methacrolein in a high state of purity. The isobutylene, substantially free of carbonylic impurities, which is distilled from the raffinate phase of the solvent extraction step, is employed as the normally gaseous hydrocarbon charge to the oxidation zone of the process.

Conditions maintained within the hydrocarbon oxidation zone of the process comprise broadly those capable of converting hydrocarbons to carbonylic reaction products comprising alpha,beta-unsaturated carbonylic compounds. Particularly preferred conditions to be maintained within the reaction zone of the process comprise the catalytic hydrocarbon oxidizing conditions set forth in

ditions hydrocarbons containing olefins having at least three carbon atoms to the molecule are converted to alpha-methylene carbonylic compounds, that is, to unsaturated aldehydes and ketones containing an olefinic linkage between two carbon atoms of aliphatic character, one of which carbon atoms is directly linked to an aldehyde or ketone group. Under the conditions of said patent the desired hydrocarbon oxidation is obtained by contact of the hydrocarbon charge in admixture with oxygen, or an oxygen-containing gas, with a cuprous oxide-containing catalyst at a temperature in the range of from about 150° C. to about 600° C., and preferably from about 200° C. to about 450° C.

Olefins having three or more carbon atoms to the molecule capable of being converted to alpha-methylene aldehydes and ketones, also referred to as vinyl-type aldehydes and ketones or alpha,-beta-unsaturated aldehydes and ketones in accordance with the invention, comprise the open- and closed-chain olefins such, as, for example, propylene; butene-1, butene-2; isobutylene; pentene-1, pentene-2; 3-methyl-butene-1; 2-methylbutene-2; hexene-1; 4-methyl-pentene-1; 3,3-dimethyl-butene-1; 4-methyl-pentene-2; octene-1; cyclopentene; cyclohexene; 3-methylcyclohexene, etc. The hydrocarbons converted to the unsaturated carbonylic compounds within the hydrocarbon oxidizing zone of the process may comprise other hydrocarbons such as, for example, paraffinic hydrocarbon of straight or open-chain structure which may or may not undergo reaction under the oxidation conditions employed within the oxidation zone of the process.

Additional materials such as, for example, normally gaseous materials or normally liquid materials which are vaporized, or which are in the gaseous state under the conditions of execution of the hydrocarbon oxidation reaction may be introduced into the hydrocarbon oxidation zone. In a preferred method of carrying out the process of the invention the hydrocarbon oxidation reaction is executed in the presence of added water vapor.

The process of the invention is applied with particular advantage to the production of alpha,-beta-unsaturated aliphatic aldehydes and ketones having three and four carbon atoms to the molecule by oxidation of normally gaseous hydrocarbons comprising olefins having from three to four carbon atoms to the molecule. In order to set forth more fully the nature of the invention it will be described in detail herein to the production of methacrolein from normally gaseous hydrocarbons comprising isobutylene with reference to the attached drawings wherein Fig. I represents a more or less diagrammatic elevational view of one form of apparatus suitable for carrying out the process of the invention, and Figs. II and III each represents a diagrammatic elevation view of an alternative form of that portion of apparatus of Fig. I between reactor 15 and absorber 30. Identical parts of the apparatus have been indicated in the figures of the drawings by like reference characters.

Referring to Fig. I of the drawing, hydrocarbons having at least three carbon atoms to the molecule, for example, a stream of normally gaseous hydrocarbons comprising isobutylene, emanating from within the system as described more fully hereinbelow, are forced through lines 10 and 11, coil 13 positioned in housing 12, and transfer line 14, into a suitable reaction zone. The reaction zone may comprise one or more

zones of enlarged cross-sectional area, such as, for example, a reaction chamber 15. The reaction zone may furthermore comprise one or more zones of restricted cross-sectional area, not shown in the drawing, such as a coil or tubular reactor. Oxygen, or an oxygen-containing gas, such as air, taken from an outside source is forced through line 17 and coil 18 into transfer line 14 wherein it mingles with the hydrocarbon stream entering reaction chamber 15.

Within reaction chamber 15 the hydrocarbon stream in admixture with the oxygen, or oxygen-containing gas, is contacted with a suitable oxidation catalyst under hydrocarbon oxidizing conditions resulting in the interaction of isobutylene and oxygen with the formation of reaction products comprising methacrolein. As indicated above, the process of the invention is not limited in its application to the use of only certain specific oxidizing conditions within reactor 15 capable of producing methacrolein. Preferred propylene oxidizing conditions, however, comprise those set forth in U. S. Patent 2,451,485 under which propylene reacts with oxygen with the formation of reaction products comprising acrolein.

Temperature conditions within reactor 15 are maintained by controlling the heat input into the streams flowing through coils 13 and 18, and optionally by other means not shown in the drawing. Steam is preferably introduced into the reaction zone. Water taken from an outside source by means of a line 20 is, therefore, forced into line 11 leading to coil 13.

Oxidation of the isobutylene-containing hydrocarbons within reactor 15 will result in the obtaining of reaction products comprising not only the desired methacrolein but other reaction products comprising, for example, saturated carbonylic compounds, such as, acetone, acetaldehyde, isobutyraldehyde, and the like, as well as substantial amount of normally gaseous reaction products such as carbon monoxide, carbon dioxide, nitrogen, etc. In addition, the reaction products will be admixed with considerable quantities of unconverted hydrocarbons and some water. In the oxidation of isobutylene at a temperature of about 360° C. in the presence of a cuprous oxide catalyst wherein the mole ratio of air to isobutylene charged to the reaction zone is approximately 5, the reactor effluence contains approximately 46.2 moles of normally gaseous material consisting predominantly of isobutylene, nitrogen, carbon dioxide, carbon monoxide, and oxygen, for each mole of total carbonyl compounds. The total carbonyl compounds in the mixture is found to have the following approximate composition:

	Per cent by weight
Methacrolein	91.6
Acetaldehyde	2.2
Propionaldehyde	1.4
Acetone	3.4
Acrolein	1.4

Practical scale operation of the process necessitates not only the efficient separation of the carbonylic reaction products from the reactor effluence but the recycling of the unconverted hydrocarbons to the reaction zone. Contrary to methods disclosed heretofore wherein substantially all normally gaseous components, including unconverted normally gaseous hydrocarbons, are separated from carbonylic compounds by a scrubbing operation employing water as scrubbing agent, the process of the present invention effects the initial separation of a fraction in the

liquid state comprising not only the carbonylic reaction products but also the unconverted normally gaseous hydrocarbons, from a gaseous fraction comprising inert gaseous components of the effluent stream from reactor 15. In accordance with the process of the invention the effluent stream from reactor 15 is passed through line 23 and cooler 24 into separator 25. Within separator 25, a liquid phase, consisting essentially of water, condensed by the lowering of the temperature of the stream occasioned by passage through cooler 24, is separated. The aqueous phase thus formed in separator 25 will comprise formaldehyde and any higher boiling polymeric material formed in reactor 15.

The reactor effluence, now free of most of its water content, may be passed directly from separator 25, through valved lines 32, 27, and 28, into an absorption zone, such as, for example, an absorber column 30. In a preferred method of carrying out the invention, however, cooling of the reactor effluence, and separation of water therefrom is effected by passage through a plurality of separate and successive coolers and separators. Thus, the stream leaving separator 25 through line 32 is preferably passed through line 32 and cooler 33 into a second separator 35. Reactor effluence now substantially free of water is passed from separator 35, through valved line 28, provided with compressor 29, into absorber 30. In effecting the cooling, and water separation, in a plurality of steps, substantially all of the water content is removed from the reactor effluence with the inclusion of not more than exceedingly small amounts of methacrolein in the aqueous phase formed in the separators.

Within absorber 30 the reactor effluence is passed upward, countercurrent to a stream of cool liquefied normally gaseous hydrocarbons comprising isobutylene, which normally gaseous hydrocarbons may constitute at least a substantial part of the entire hydrocarbon charge to the system. The normally gaseous hydrocarbons comprising isobutylene, emanating from an outside source, are forced through line 37 provided with cooling means, such as a cooler 38, into the upper part of absorber 30. The hydrocarbons emanating from cooler 38 are at a temperature sufficiently low to assure the introduction of at least the greater part of the normally gaseous hydrocarbon stream into the upper part of absorber 30 in the liquid state. Conditions within absorber 30 are controlled to obtain the absorption, by the liquid normally gaseous hydrocarbon stream introduced through line 37, of substantially all of the carbonylic compounds contained in the stream entering absorber 30 through line 28, and preferably also the condensation of at least a substantial part of unconverted olefinic hydrocarbons.

Although but a single absorber column is shown in the drawing it is to be understood that a plurality of two or more such absorption col-

umns may be employed within the scope of the invention and the hydrocarbon feed to the process apportioned to each of the absorber columns. The invention is furthermore not limited to the use of a column-type absorber and any suitable type of contacting device may be comprised in the absorption zone enabling efficient contact of the hydrocarbon charge and the effluent stream from reactor 15.

The temperature at which the absorption is carried out within absorber 30 may vary considerably within the scope of the invention in accordance with the nature of the components comprised in the reactor effluence, and of the hydrocarbon feed to the system, and the pressure employed. Care is taken to maintain the temperature within absorber 30 below that at which any substantial vaporization of the olefinic hydrocarbon components of the streams charged thereto will take place. Thus, in the production of methacrolein from normally gaseous hydrocarbons comprising isobutylene the absorption may be carried out at pressures within the range of from about 100 to about 300 pounds within the absorber 30. Temperature conditions within absorption column 30 are maintained with the aid of coolers 24, 33 and 38, and optionally by other temperature controlling means not shown in the drawing.

The following example is illustrative of the advantages inherent in the method of separating carbonylic compounds from the oxidation zone effluent stream by absorption in normally gaseous hydrocarbon charge to the process.

EXAMPLE I

In two separate operations isobutylene is oxidized to methacrolein-containing reaction products by contacting a mixture of isobutylene and oxygen, containing a mole ratio of isobutylene to oxygen of 5, with a cuprous oxide catalyst at a temperature of about 360° C. The resulting reaction mixture is cooled and compressed to the pressure at which a liquid isobutylene phase begins to appear. The residual gaseous phase of the compressed reaction mixture is introduced into an absorber column wherein it is contacted countercurrently with a stream of liquefied isobutylene. The rate of introduction of the liquefied isobutylene into the upper part of the absorber is controlled to result in the obtaining of a methacrolein absorption of 99.9%. Each of the two operations is repeated under substantially identical conditions with the exception that water is substituted for the liquefied isobutylene stream introduced into the upper part of the absorber. The absorption is carried out in the column having the equivalent of ten theoretical plates. Temperature and pressure of the absorption and amount of solvent required to obtain the desired degree of separation are indicated in the following table for each of the separate operations.

Table I

Temp., °C.	Pres- sure, P.s.i.a.	Absorp- tion Solvent	Feed to Absorber (Moles)			Solvent Requirements (Moles)	Moles Sol- vent per mole Metha- rolein in Absorber Feed
			Metha- rolein	Isobu- tylene	Total feed		
20	70.4	Isobutylene	0.743	24.0	45.8	8.11	10.9
30	95.5	do	0.793	24.0	46.0	7.52	9.48
20	70.4	Water	0.743	24.0	45.8	205	276
30	95.5	do	0.793	24.0	46.0	247	312

Enriched absorbing medium (absorbate) consisting essentially of normally gaseous hydrocarbons comprising isobutylene in admixture with methacrolein-containing carbonylic reaction products are passed from the lower part of absorber 30, through valved lines 39 and 40, into a suitable distillation zone comprising, for example, a fractionating column 41. Within column 41 the enriched absorbent (absorbate) emanating from column 30 is fractionated to separate a gaseous fraction comprising normally gaseous hydrocarbons comprising isobutylene from a liquid fraction comprising methacrolein-containing carbonylic reaction products. The carbonylic compounds produced in reactor 15, as shown above, will comprise saturated carbonylic impurities inseparable from the isobutylene by ordinary fractionating means. Thus, the unsaturated carbonylic by-products, unavoidably produced in the oxidation of isobutylene to methacrolein will include acetaldehyde. Acetaldehyde cannot be removed from isobutylene by ordinary fractionating means due to the existence of an azeotrope between the two compounds. At a pressure of 28 pounds per square inch absolute the azeotropic mixture of isobutylene and acetaldehyde is found to contain 7.0% acetaldehyde. The normally gaseous hydrocarbons comprising isobutylene separated within fractionator 41 as a gaseous fraction will therefore be contaminated by the presence therein of saturated carbonylic impurities comprising acetaldehyde. In continuous operation the direct passage of such a contaminated stream to the oxidation zone of the process would result in the accumulation of the impurity within the system to a degree seriously militating against the obtaining of the optimum operating conditions. The liquid fraction comprising methacrolein-containing carbonylic compounds separated in fractionator 41 will comprise methacrolein in admixture with saturated carbonylic compounds such as acetone, isobutyaldehyde, acetaldehyde, propionaldehyde, etc., from which the methacrolein generally must be separated in a high state of purity. Simultaneous recovery of methacrolein in a high state of purity from the methacrolein-containing carbonylic reaction products, and removal of acetaldehyde impurity from the normally gaseous hydrocarbons comprising isobutylene is accomplished by passing the liquid fraction comprising methacrolein-containing carbonylic compounds from fractionator 41 through valved lines 44 and 39 into a solvent treating zone comprising, for example, extraction column 45. Within column 45 the methacrolein-containing carbonylic compounds are subjected to a liquid-liquid solvent extraction using water as a solvent in the presence of a secondary organic solvent. To this effect, water is introduced into the upper part of column 45 by means of valved line 47 provided with suitable cooling means such as a cooler 48. The vapor fraction consisting essentially of normally gaseous hydrocarbons comprising isobutylene contaminated with acetaldehyde which is separated in fractionator 41, is passed from fractionator 41, through valved lines 51, 52 and 53, and through cooler 54, into extraction column 45 as the secondary organic solvent used therein. In passing through cooler 54 the hydrocarbon stream is cooled to a temperature sufficiently low to assure that at least the greater part of the normally gaseous hydrocarbon stream comprising isobutylene is introduced into column 45 in the liquid phase.

The normally gaseous hydrocarbon stream is introduced into column 45 at a point below the introduction of the methacrolein-containing carbonylic compounds into the extraction column. The specific temperature conditions maintained within the extractor column 45 may vary within the scope of the invention depending to some extent upon the particular composition of the materials charged thereto. In the purification of a methacrolein-containing carbonylic product obtained by the oxidation of isobutylene in the presence of a cuprous oxide catalyst and using acetaldehyde-contaminated normally gaseous hydrocarbons comprising isobutylene as the secondary solvent, temperatures below about 30° C., for example, in the range of from about 0° C. to about 20° C. have been found suitable. The invention is, however, in no wise limited to the use of only these specific conditions within column 45 and the conditions set forth broadly in co-pending application Serial No. 84,074, filed March 29, 1949, which is directed to the purification of olefin-oxidation products, may suitably be applied.

It is to be pointed out that the proportion of isobutylene-containing hydrocarbons separated from methacrolein-containing carbonylic compound in fractionator 41 may vary within the scope of the invention. In general, general conditions are controlled to pass sufficient isobutylene-containing hydrocarbons overhead therein to provide the amount required to function as part or all of the secondary organic solvent stream introduced into the lower part of column 45. A valved line 55 is provided to enable the passage of additional amounts of isobutylene into line 53 should this be required. If desired, at least a part of the liquid fraction taken from column 30 through line 39 may be caused to by-pass fractionator 41 and be introduced directly into the solvent extraction column 45, by judicious manipulation of valves 56 and 57 in lines 39 and 40, respectively.

Under the above conditions a raffinate phase will be formed in the upper part of column 45 consisting essentially of methacrolein and normally gaseous hydrocarbons comprising isobutylene which is substantially free of saturated carbonylic impurities, such as acetaldehyde. The raffinate phase formed in column 45 is passed through line 60 into a stripping column 61. In column 61 the raffinate phase is fractionated to separate a vapor fraction consisting essentially of normally gaseous hydrocarbons comprising isobutylene substantially free of saturated carbonylic compounds, such as acetaldehyde, from a liquid fraction consisting essentially of methacrolein in a high state of purity.

The liquid fraction consisting essentially of high purity methacrolein is taken from column 61 through valved line 63 as a final product.

The vapor fraction consisting essentially of normally gaseous hydrocarbons comprising isobutylene substantially free of carbonylic compounds, is passed from fractionator 61 through valved line 10 into line 11. It is thus seen that the hydrocarbon charge to reactor 15 comprises the normally gaseous hydrocarbons comprising isobutylene which have functioned not only as the absorbing agent for the carbonylic products in absorber 30 but also as the secondary organic solvent used in the solvent extraction column 45 of the process. It is to be noted that in thus functioning in such dual capacity within the system prior to its passage into the reaction

zone, the hydrocarbon feed to the system enables the realization of the advantages inherent in its use as the absorbent in the carbonylic product absorber of the process without incurring the introduction of a contaminated hydrocarbon charge into the reaction zone.

Valved line 64, provides communication between lines 10 and 53, and valved line 66, provides communication between lines 10 and 37. An aqueous extract phase comprising the saturated carbonylic compounds introduced into column 45, including, for example, acetone, isobutyraldehyde, propionaldehyde, acetaldehyde, etc., and water, is formed within extraction column 45 and eliminated therefrom through valved line 68.

The aqueous phase separated in separators 25 and 35 is eliminated therefrom through valved lines 10 and 71, respectively. The aqueous phase thus drawn from separators 25 and 35 will generally comprise only minor amounts of methacrolein and may be eliminated from the system through valved lines 72 and 73. Residual amounts of carbonylic constituents, including any methacrolein, contained in the aqueous phase separated in separators 25 and 35 may be removed therefrom, however, by any suitable means, such as, for example, by distillation in a still 74. Carbonylic constituents comprising methacrolein are taken overhead from still 74 and passed through line 75 into line 39. Aqueous bottoms are removed from still 74 by means of valved line 76.

Substantially all carbonylic reaction products are recovered therefore from the effluent stream leaving the hydrocarbon oxidation zone of the process without the need for any solvent for the absorption operation other than the hydrocarbon feed to the process.

Overhead from the absorber 39 will comprise a mixture of inert gases saturated with normally gaseous hydrocarbons comprising isobutylene. Residual amounts of isobutylene remaining in the gaseous overhead from absorber 39 are readily separated economically therefrom because of the reduction in volume over the amount of gases normally encountered in operation wherein substantially all of the hydrocarbons are comprised in the absorber overhead. The gaseous stream passing through line 81 may therefore be passed to suitable means for the recovery of isobutylene therefrom.

Suitable means for the recovery of residual isobutylene from the overhead of column 20 may comprise a second absorption zone comprising absorption column 81, wherein the gaseous stream is contacted countercurrently with a descending absorbent stream, such as a higher boiling hydrocarbon stream, for example, a gas oil, introduced into the upper part of column 81 by means of valved line 82. In column 81 isobutylene is absorbed by the gas oil stream and inert tail gas, comprising oxides of carbon, nitrogen, etc., is eliminated from the system through valved line 83. Gas oil enriched with absorbed isobutylene, is passed through line 84 to a suitable still 85 wherein isobutylene is flashed off. Isobutylene may be passed through valved line 91 into line 10. In a preferred method of carrying out the invention, even the isobutylene flowing through line 90 is passed, at least in part, into line 53 to be used as part of the secondary organic solvent in column 45 before passing to the oxidation zone. In this wise substantially all contaminant saturated carbonylic compounds are removed from all hydrocarbons

passed to the oxidation zone. Lean scrubbing medium is returned from the lower part of stripper 85, through lines 86 and 82, to the upper part of absorber column 81.

It is to be understood that modifications within the scope of the invention may be made in the process as set forth in the foregoing detailed illustrative description thereof. Thus, modifications may be made in the method employed in 10 cooling the stream passing from reactor 15 to absorber 30, and in the removal of water therefrom. In a modification of the process of the invention, as illustrated by Fig. II of the attached drawing, the effluent stream leaving reactor 15 through line 23 is cooled in suitable cooling means, such as, for example, a cooler 24, and thereafter compressed to a high pressure. Thus, the cooled stream leaving cooler 24 is passed into compressor 96 wherein it is compressed, and thence through line 97 into a phase separator chamber 100. Additional cooling means, such as, for example, a cooler 98, are provided to cool the compressed stream flowing through line 97. Further cooling means may be resorted to, for example, the introduction of a quenching medium, such as, water, into line 97 from an outside source by means of valved line 99. In passing through compressor 96 the cooled reactor effluence is compressed to a pressure sufficiently high to enable the formation of three phases, two liquid phases and a vapor phase, within separator 100. The lower liquid phase will consist essentially of water containing formaldehyde and any higher polymeric reaction products formed in the system. The intermediate liquid layer will consist essentially of isobutylene and methacrolein-containing carbonylic reaction products. The vapor phase will comprise methacrolein-containing carbonylic reaction products, hydrocarbons, and normally gaseous components of the reactor effluence. The lower aqueous phase is passed from separator 100 through line 103 into still 54 wherein carbonylic constituents are distilled therefrom as described above. The intermediate liquid phase, consisting of isobutylene and methacrolein-containing carbonylic reaction products is passed through line 102 into line 39. The vapor phase is passed from separator 100 through line 101 into absorber 30 to be treated therein as described above. The modification of 30 the process wherein the reactor effluence is compressed to a high pressure reduces substantially the load placed upon absorber 30.

A method of cooling the reactor effluence particularly preferred in the production of acrolein by the oxidation of propylene is illustrated by the Fig. III of the attached drawing. Therein the effluent emanating from reactor 15 through line 23 is passed through line 105 into a suitable quenching chamber such as, for example, a tower 107. Baffles, bubble trays, inert packing, or the like may be provided in tower 107. Suitable heat exchanging means such as, for example, an indirect heat exchanger 106, may be provided in line 105 to enable the withdrawal of heat from the stream flowing through line 23 by indirect heat exchange with a suitable cooling agent which may comprise a side-stream taken from within the system. Within tower 107 the reactor effluence is passed upwardly countercurrent to a stream of water introduced into the upper part of tower 107 by means of line 108. Heating means such as, for example, a reboiler or a closed heating coil 109, is provided in the lower part of tower 107. Conditions within tower 107 are controlled to effect the separation therein of aqueous

liquid bottoms containing substantially all formaldehyde and higher boiling polymeric materials formed in the system, but containing no substantial amount of acrolein. Liquid bottoms are withdrawn from tower 107 and continuously recirculated to the upper part of tower 107 by means of line 108 provided with pump 111. Means for controlling the temperature of the water introduced into the upper part of tower 107, such as a cooler, or a heat exchanger 112, is provided in line 108. Conditions within tower 107 enabling the separation of substantially all water of reaction as bottoms, with the passage of substantially all of the desired unsaturated aldehyde overhead, is obtained by control of the temperature of the bottoms in the tower and the water introduced into the top thereof by means of coil 109 and exchanger 112, respectively. An amount of water generally at least equal to the amount of water introduced into, or formed within, the reaction zone is bled intermittently or continuously from the system through valved line 113. A valved line 114 is provided for the introduction of water into line 108. In cooling the reactor effluce, and separating water therefrom, by the method substantially as illustrated by the Fig. III of the drawing, not more than exceedingly small amounts of the desired unsaturated aldehyde, such as acrolein, will be contained in the aqueous stream eliminated from the system through valved line 113. The aqueous stream drawn from tower 107 through valved line 113 may be subjected to conventional processing means not shown in the drawing comprising, for example, one or more such steps as distillation, extractive distillation, absorption, and the like, to recover therefrom any carbonylic compounds which may be contained therein. Overhead from tower 107, consisting of effluce from reactor 15 now free of any substantial amount of water, is passed through line 115 into absorber 30, to be treated therein as described in the present detailed description of the invention.

For the purpose of clarity, all parts of apparatus not essential to a complete description of the invention such as, for example, pumps, condensers, accumulators, etc., have been omitted from the drawing and the description of the invention.

EXAMPLE II

In two separate operations, A and B, methacrolein of high purity is produced by the direct oxidation of isobutylene in accordance with the invention. The results obtained in each of the separate operations are given throughout the example under separate columns A and B, respectively.

Isobutylene is oxidized to methacrolein by contacting a mixture of isobutylene and air, containing a ratio of isobutylene to oxygen of 5, with a cuprous oxide catalyst in the presence of added steam at a temperature of about 360° C. The reactor effluce contains approximately:

	A	B
Isobutylene.....moles	24.0	24.0
Water.....do	53.7	53.7
Total Carbonyl Compounds.....do	1.31	1.31

for each 100 moles of reactor effluce. The remainder of the reactor effluce consists predominantly of normally gaseous materials such

75

as nitrogen, carbon monoxide, carbon dioxide, oxygen. The total carbonylic compounds in the mixture has the following approximate composition in mole percent.

	A	B
Methacrolein.....	89.2	89.2
Propionaldehyde.....	1.68	1.68
Acetaldehyde.....	3.43	3.43
Acetone.....	3.97	3.97
Acrolein.....	1.68	1.68

The total reactor effluce is compressed, cooled, and introduced into a phase separator resulting in the formation of two distinct liquid phases and a gas phase in the phase separator. The temperature and pressure, and the distribution of the methacrolein and isobutylene (based on 100 moles of reactor effluce) in the phase, separator are as follows:

	Phase Separator	A	B
Temp., °C.....	20	30	
Pressure, lbs. sq. in. abs.....	114.7	114.7	
Gas phase:			
isobutylene content, moles.....	9.87	17.3	
methacrolein content, moles.....	.0879	0.235	
Isobutylene liquid phase:			
isobutylene content, moles.....	14.13	6.7	
methacrolein content, moles.....	0.957	0.78	
Aqueous phase:			
isobutylene content, moles.....	0.123	0.155	
methacrolein content, moles.....			

The gas phase is passed from the phase separator into an absorber column wherein it is brought into countercurrent contact with a stream of liquefied isobutylene which is introduced into the upper part of the absorber from an outside source. The temperature and pressure in the absorber, and the amount of isobutylene introduced as solvent for each mole of methacrolein introduced into the absorber to obtain the absorption of about 99.0% of the methacrolein in the isobutylene solvent are as follows:

	Absorber	A	B
Temperature, °C.....	20	30	
Pressure, lbs. sq. in. abs.....	114.7	114.7	
Isobutylene solvent required, moles per mole methacrolein in absorber feed.....	21.6	14.9	
Methacrolein absorption.....	98.9	99.6	

Liquid isobutylene containing the absorbed methacrolein - containing carbonylic reaction products is taken from the absorber and distilled at 28 lbs. sq. in. abs. to strip isobutylene therefrom. Results obtained are as follows:

	Absorbate Stripping	A	B
Overhead Composition:			
Isobutylene, mole percent.....	99.9	99.9	
Acetaldehyde, mole percent.....	.1	.09	
Bottoms—Composition:			
Methacrolein, mole percent.....	96.2	97.1	
Propionaldehyde mole percent.....	1.1	1.3	
Acetone.....	1.1	.8	
Acrolein.....	1.6	.8	

The crude methacrolein-containing carbonylic products remaining after stripping the absorbate are combined with the isobutylene liquid phase from the phase separator and the mixture subjected to a liquid phase extraction in a 20 plate extraction column using water as the solvent in the presence of a secondary organic solvent. The acetaldehyde-contaminated isobutylene stripped

from the absorbate is liquefied and with the addition of some supplementary isobutylene is used as the secondary organic solvent. The water solvent is introduced into the upper part of the column, the isobutylene into the lower part, and the methacrolein-containing carboxylic compounds into an intermediate part of the column. A raffinate phase consisting essentially of methacrolein and isobutylene is taken from the upper part of the extraction column. An aqueous phase consisting essentially of water and saturated carboxylic compounds including isobutyraldehyde, acetaldehyde, acetone, propionaldehyde, etc., is taken from the lower part of the column.

Liquefied propylene, taken from an outside source, is introduced into the top of the absorber column at a controlled rate to obtain absorption of 99.9+ % of the acrolein content of the reaction mixture charged to the absorber column. The absorption is carried out at a temperature of 20° C. and at a pressure of 260 pounds per square inch absolute. The operation is repeated under substantially identical conditions with the exception that water is substituted for the liquefied propylene stream introduced into the absorption column. The amount of solvent required in each operation to obtain the desired degree of separation is indicated in the following table:

Absorber Solvent	Feed to Absorber—Moles			Solvent requirements per 100 moles absorber feed	Mole Ratio solvent required to acrolein in absorber feed
	Acrolein	Propylene	Total Feed		
Propylene	0.103	16.1	28.3	5.20	50.5
Water	0.103	16.1	28.3	18.1	176

Conditions and results of the liquid extraction are as follows:

Liquid Phase Extraction	A	B
Temp. of Extraction, °C	20	30
Pressure, lbs. per sq. in. abs.	37.8	51.2
Isobutylene entering with carboxylic feed, moles	14.7	6.7
Isobutylene entering as secondary solvent, moles	4.8	2.3
Water entering as solvent, moles	40.0	30.0
Methacrolein recovery, percent of feed	99.9+	99.9+
Composition of raffinate:		
Isobutylene, moles	19.3	9.0
Methacrolein, moles	1.01	1.01

Isobutylene is stripped from the raffinate containing less than 0.25 mole percent saturated carboxylic compounds leaving as residue methacrolein of 99.5% purity.

The isobutylene stripped from the raffinate phase of the liquid extraction step is used as charge to the oxidation reactor.

EXAMPLE III

Propylene is oxidized by contacting a mixture of propylene and air containing a mole ratio of propylene to oxygen of 6 with a cuprous oxide catalyst at a temperature of about 375° C. in a reactor. The reactor effluence is introduced into a quench tower wherein it passes upward countercurrent to a stream of water introduced into the upper part of the quench tower. The water introduced into the upper part of the tower is maintained at a temperature of from 20 to 50° C. The bottoms of the quench tower are maintained at a temperature of 80° C. to 100° C. Liquid aqueous bottoms containing formaldehyde are withdrawn from the lower part of the quench tower. The cooled effluence now free of any substantial amount of water, is passed overhead from the quench tower into an absorber column having a capacity equivalent to ten theoretical plates. The reactor effluence introduced into the absorber column contained 29.3 moles of normally gaseous material consisting predominantly of propylene, carbon monoxide, carbon dioxide, nitrogen, and oxygen, for each mole of total carboxylic compounds. The total carboxylic compounds in the mixture had the following composition:

	Percent by weight
Acrolein	90.0
Acetaldehyde	6.0
Propionaldehyde	2.0
Acetone	2.0

EXAMPLE IV

25 The absorbate consisting of the acrolein-containing carboxylic reaction products absorbed in propylene in the foregoing Example III is introduced into a distillation column and propylene stripped therefrom. The acrolein-containing 30 carboxylic residue is subjected to liquid phase extraction using water as solvent in the presence of a secondary solvent. The propylene stripped from the carboxylic compounds-containing absorbate is liquefied and is used as secondary organic solvent in the liquid phase extraction. A raffinate phase consisting essentially of acrolein and propylene is taken from the upper part of the column and an aqueous phase consisting essentially of water and saturated carboxylic compounds including acetone, acetaldehyde, propionaldehyde, etc. is taken from the lower part of the extraction column. Conditions used and results obtained in the extraction of the crude acrolein-containing carboxylic reaction product are as follows:

45 Liquid phase extraction:

Temperature, °C	20
Pressure, lbs. sq. in. abs.	150
Water entering as solvent	14.3
Propylene entering as solvent	10.0
Acrolein recovery	98.5
Composition raffinate per cent by weight:	
Propylene	90
Acrolein	10

55 Propylene is stripped from the raffinate phase and used as charge to the propylene oxidation reactor. Acrolein of a purity of 96.2% remained after distilling the propylene from the raffinate phase.

60 The invention claimed is:

1. In a process for the production of methacrolein wherein normally gaseous hydrocarbons comprising isobutylene are subjected to isobutylene oxidizing conditions in a reaction zone with the formation of a reaction mixture comprising methacrolein, acetaldehyde-containing saturated carboxylic compounds, normally gaseous hydrocarbons comprising isobutylene and fixed gases, 65 the steps which comprise contacting at least a part of said reaction mixture with liquefied normally gaseous hydrocarbons comprising isobutylene, thereby forming a gaseous phase comprising said fixed gases and a liquid absorbate comprising isobutylene-containing normally gas-

eous hydrocarbons, methacrolein and acetaldehyde-containing saturated carbonylic compounds, stripping acetaldehyde-containing normally gaseous hydrocarbons comprising isobutylene from said absorbate, thereby leaving a residue comprising methacrolein-containing carbonylic compounds, extracting said residue with water flowing countercurrent to an organic solvent comprising isobutylene-containing normally gaseous hydrocarbons in an extraction zone, introducing said acetaldehyde-containing normally gaseous hydrocarbons stripped from said absorbate into said extraction zone in the liquid state to be used therein as said organic solvent, thereby forming a raffinate phase comprising methacrolein and isobutylene-containing normally gaseous hydrocarbons substantially free of saturated carbonylic compounds in said extraction zone, stripping isobutylene-containing normally gaseous hydrocarbons from said raffinate phase, and passing normally gaseous hydrocarbons comprising isobutylene stripped from said raffinate phase into said reaction zone.

2. In a process for the production of methacrolein wherein normally gaseous hydrocarbons comprising isobutylene are subjected to isobutylene oxidizing conditions in a reaction zone with the formation of a reaction mixture comprising methacrolein-containing saturated carbonylic compounds, normally gaseous hydrocarbons comprising isobutylene and fixed gases, the steps which comprise contacting at least a part of said reaction mixture with liquefied normally gaseous hydrocarbons comprising isobutylene, thereby forming a gaseous phase comprising said fixed gases and a liquid absorbate comprising isobutylene-containing normally gaseous hydrocarbons, and methacrolein-containing saturated carbonylic compounds, stripping normally gaseous hydrocarbons comprising isobutylene from said absorbate, thereby leaving a residue comprising carbonylic compounds, extracting said residue with water flowing countercurrent to an organic solvent comprising isobutylene-containing normally gaseous hydrocarbons in an extraction zone, introducing said normally gaseous hydrocarbons stripped from said absorbate into said extraction zone in the liquid state to be used therein as said organic solvent, thereby forming a raffinate phase comprising methacrolein and isobutylene-containing normally gaseous hydrocarbons substantially free of saturated carbonylic compounds in said extraction zone, stripping normally gaseous hydrocarbons comprising isobutylene from said raffinate phase, and passing normally gaseous hydrocarbons comprising isobutylene stripped from said raffinate phase into said reaction zone.

3. In a process for the production of acrolein wherein normally gaseous hydrocarbons comprising propylene are subjected to propylene oxidizing conditions in a reaction zone with the formation of a reaction mixture comprising acrolein-containing saturated carbonylic compounds, normally gaseous hydrocarbons comprising propylene and fixed gases, the steps which comprise contacting at least a part of said reaction mixture with liquefied normally gaseous hydrocarbons comprising propylene, thereby forming a gaseous phase comprising said fixed gases and a liquid absorbate comprising propylene-containing normally gaseous hydrocarbons and acrolein-containing saturated carbonylic compounds, stripping normally gaseous hydrocarbons comprising propylene from said absorbate, there-

by leaving a residue comprising acrolein-containing carbonylic compounds, extracting said residue with water flowing countercurrent to an organic solvent comprising propylene-containing normally gaseous hydrocarbons in an extraction zone, introducing said normally gaseous hydrocarbons stripped from said absorbate into said extraction zone in the liquid state to be used therein as said organic solvent thereby forming a raffinate phase comprising acrolein and propylene-containing normally gaseous hydrocarbons substantially free of saturated carbonylic compounds in said extraction zone, stripping normally gaseous hydrocarbons comprising propylene from said raffinate phase, and passing normally gaseous hydrocarbons comprising propylene stripped from said raffinate phase into said reaction zone.

4. In a process for the production of an alpha-methylene aldehyde having three to four carbon atoms to the molecule wherein normally gaseous hydrocarbons comprising an olefin having three to four carbon atoms to the molecule are subjected to olefin oxidizing conditions in a reaction zone with the formation of a reaction mixture comprising an alpha-methylene aldehyde having three to four carbon atoms to the molecule in admixture with saturated carbonylic compounds, normally gaseous hydrocarbons, and fixed gases, the steps which comprise contacting at least a part of said reaction mixture with liquefied normally gaseous hydrocarbons comprising an olefin having three to four carbon atoms to the molecule, thereby forming a gaseous phase comprising said fixed gases and a liquid absorbate comprising said liquefied normally hydrocarbons and said alpha-methylene aldehyde-containing saturated carbonylic compounds, stripping said normally gaseous hydrocarbons from said absorbate, thereby leaving a residue comprising alpha-methylene aldehyde-containing carbonylic compounds, extracting said residue with water flowing countercurrent to an organic solvent in an extraction zone, introducing said normally gaseous hydrocarbons stripped from said absorbate into said extraction zone in the liquid state to be used therein as said organic solvent, thereby forming a raffinate phase comprising alpha-methylene aldehyde having three to four carbon atoms to the molecule and normally gaseous hydrocarbons comprising an olefin having three to four carbon atoms to the molecule substantially free of saturated carbonylic compounds in said extraction zone, stripping said normally gaseous hydrocarbons from said raffinate phase and passing said normally gaseous hydrocarbons stripped from said raffinate phase into said reaction zone.

5. In a process for the production of an alpha-methylene aldehyde having at least three carbon atoms to the molecule wherein hydrocarbons comprising an olefin having at least three carbon atoms to the molecule are subjected to olefin oxidizing conditions in a reaction zone with the formation of a reaction mixture comprising an alpha-methylene aldehyde having at least three carbon atoms to the molecule in admixture with saturated carbonylic compounds, unconverted hydrocarbons, and fixed gases, the steps which comprise contacting at least a part of said reaction mixture with a liquid stream of said hydrocarbons to be oxidized comprising an olefin having at least three carbon atoms to the molecule, thereby forming a gaseous phase comprising fixed gases and a liquid absorbate com-

prising said hydrocarbons to be oxidized in admixture with said alpha-methylene aldehyde-containing saturated carbonylic compounds, stripping said hydrocarbons to be oxidized from said absorbate, thereby leaving a residue comprising alpha-methylene aldehyde-containing carbonylic compounds, extracting said residue with water flowing countercurrent to an organic solvent in an extraction zone, introducing said hydrocarbons stripped from said absorbate into said extraction zone in the liquid state to be used therein as said organic solvent, thereby forming a raffinate phase comprising alpha-methylene aldehyde having at least three carbon atoms to the molecule and said hydrocarbons to be oxidized comprising an olefin having at least three carbon atoms to the molecule substantially free of saturated carbonylic compounds in said extraction zone, stripping said hydrocarbons to be oxidized from said raffinate phase, and passing said hydrocarbons stripped from said raffinate phase into said reaction zone.

6. In a process for the production of an unsaturated carbonylic compound of the group consisting of alpha-methylene aldehydes and ketones having three to four carbon atoms to the molecule wherein normally gaseous hydrocarbons comprising an olefin having three to four carbon atoms to the molecule are subjected to olefin oxidizing conditions in a reaction zone with the formation of a reaction mixture comprising an unsaturated carbonylic compound of the group consisting of alpha-methylene aldehydes and ketones having three to four carbon atoms to the molecule in admixture with saturated carbonylic compounds, unconverted normally gaseous olefin, and fixed gases, the steps which comprise contacting at least a part of said reaction mixture with liquefied normally gaseous hydrocarbons comprising an olefin having three to four carbon atoms to the molecule thereby forming a gaseous phase comprising said fixed gases and a liquid absorbate comprising said normally gaseous hydrocarbons and said unsaturated carbonylic compound in admixture with saturated carbonylic compounds, stripping said normally gaseous hydrocarbons from said absorbate, thereby leaving a residue comprising said unsaturated carbonylic compound in admixture with carbonylic compounds, extracting said residue with water flowing countercurrent to an organic solvent in an extraction zone, introducing said normally gaseous hydrocarbons stripped from said absorbate into said extraction zone in the liquid state to be used therein as said organic solvent, thereby forming a raffinate phase comprising said unsaturated carbonylic compound having three to four carbon atoms to the molecule and said nor-

mally gaseous hydrocarbons comprising an olefin having three to four carbon atoms to the molecule free of saturated carbonylic compounds in said extraction zone, stripping said normally gaseous hydrocarbons from said raffinate phase, and passing said hydrocarbons stripped from said raffinate phase into said reaction zone.

7. In a process for the production of an alpha-beta-unsaturated carbonylic compound wherein hydrocarbons comprising an olefin having at least three carbon atoms to the molecule are subjected to olefin oxidizing conditions in a reaction zone with the formation of a reaction mixture comprising an alpha,beta-unsaturated carbonylic compound in admixture with saturated carbonylic compounds, unconverted hydrocarbons, and fixed gases, the steps which comprise contacting at least a part of said reaction mixture with a liquid stream of hydrocarbons to be oxidized comprising an olefin having at least three carbon atoms to the molecule, thereby forming a gaseous phase comprising said fixed gases and a liquid absorbate comprising said hydrocarbons to be oxidized and said alpha,beta-unsaturated carbonylic compound in admixture with saturated carbonylic compounds, stripping said hydrocarbons from said absorbate, thereby leaving a residue comprising said alpha,beta-unsaturated carbonylic compound in admixture with saturated carbonylic compounds, extracting said residue with water flowing countercurrent to an organic solvent in an extraction zone, introducing said hydrocarbons to be oxidized stripped from said absorbate into said extraction zone in the liquid state to be used therein as said organic solvent, thereby forming a raffinate phase comprising said alpha,beta-unsaturated carbonylic compound and said hydrocarbons to be converted comprising an olefin having at least three carbon atoms to the molecule free of saturated carbonylic compounds in said extraction zone, stripping said hydrocarbons to be converted from said raffinate phase, and passing said hydrocarbons stripped from said raffinate phase into said reaction zone.
